UNITED STATES PATENT OFFICE.

ALBERT J. DANIELSON, OF LOS ANGELES, CALIFORNIA.

FOLDING UMBRELLA.

Application filed August 4, 1922. Serial No. 579,640.

The prime object of this invention is to provide a folding umbrella that can be readily operated to be folded so that an umbrella of average length can be compactly folded, that it may be easily placed in a medium size handbag or carried in the pocket of a raincoat when not being used.

A further object of my invention is to provide a folding umbrella having telescopic sections that may be withdrawn and locked in position to provide a handle of the average length umbrella.

A still further object of my invention is to provide a folding umbrella that will stretch a cover of the average size umbrella with the use of ribs and whereby the ribs may be locked to hold the cover in a spread position and to so construct the ribs that upon sliding of the rib ring on the telescopic handle section, that a series of outer ribs will be swung inwardly and upwardly thus bringing the cover and ribs into a folded position.

And a still further object of my invention is to provide an umbrella of the above indicated character wherein the various parts can be locked against movement when the same are in a folded position.

An additional object of my invention is to provide a folding umbrella of the above indicated character that can be folded for conveniently carrying the same in a handbag or the pocket of a coat, thus reducing to a minimum the possibility of losing the umbrella as is frequently the case at the present time due to the fact that in order to use both hands the owners of an umbrella will set same aside while conducting their business and afterwards walk out leaving the umbrella standing in a corner or hanging on the back of a chair.

These and like objects of my invention will be better understood as the description follows and as is specifically pointed out in the appended claim.

Referring to the accompanying drawings which form a part of this specification and which clearly illustrate the construction and operation of my invention,

Figure 1 is a perspective view of an umbrella constructed in accordance with my invention.

Figure 2 is a top plan view of the cover, showing the ribs in dotted lines.

Figure 3 is an enlarged fragmentary sec-

tion showing the connection between the outer ribs and inner ribs.

Figure 4 shows a modified form of connecting the outer ribs with the inner ribs.

Figure 5 is a vertical central section 60 through an open umbrella, showing the telescopic handle sections partly in section.

Figure 6 is a side elevation of an umbrella constructed in accordance with my invention showing same in a folded position, 65 with the cover removed.

Figure 7 is a fragmentary section showing the pivotal connection of one of the stretcher rods with the sliding stretcher ring. 70

Figure 8 is a transverse section of same.

Figure 9 is an enlarged fragmentary vertical section through two of the telescopic sections, showing means for locking same in an adjusted position. 75

Figure 10 is an enlarged fragmentary vertical section showing the means for locking the various parts in a folded position.

Figure 11 is an enlarged fragmentary vertical section showing the means for supporting the stretcher ring in engagement with one of the telescopic sections, and 80

Figure 12 is a horizontal section taken on line 12-12 of Figure 10.

Referring to the accompanying drawings in detail, like characters will be used to designate like parts in the different views.

In the drawings, the numeral 1 designates the hand grip portion of the telescopic handle which comprises in addition to the hand grip 1 sections 2 and 3. The sections 1, 2, and 3 are hollow and the last named section is provided adjacent one end with the usual crown 4 and a cap 5 is formed on the end of said section to form a closure for same. 90

A series of inner ribs 6 having one end connected to the crown 4 in any of the usual methods employed in the manufacture of umbrellas, and the outer ends of the inner ribs 6 are bent at right angles as at 7 to provide a shaft on which a crank 8 is free to rotate. A series of outer ribs 9, two of which comprises a set for operation in connection with each of the inner ribs. The outer ribs 9 have the outer ends secured to the cloth cover of the umbrella in the usual way as at 10, while the inner ends of the outer ribs are pivotally connected at 11 to a plate 12. An extension 13 is formed on the plate 12 and terminates into a shaft 14 which 95

provide a shaft on which a crank 8 is free to rotate. A series of outer ribs 9, two of which comprises a set for operation in connection with each of the inner ribs. The outer ribs 9 have the outer ends secured to the cloth cover of the umbrella in the usual way as at 10, while the inner ends of the outer ribs are pivotally connected at 11 to a plate 12. An extension 13 is formed on the plate 12 and terminates into a shaft 14 which 100

105

110

is positioned within the hollow end 15 of the crank 8, and provided with a shoulder for permitting but a slight pivotal movement of the plate 12 with relation to the crank 8, the purpose of which will be better understood as the description follows.

A series of rib stretching rods 16 are each pivotally connected at one end to a stretcher ring 17 that is slideable on the hollow telescopic section 3. The stretcher ring 17 is provided with flanges 18 struck out from same to which a plate 19 is pivotally supported to permit stretcher rods 16 to engage the ring 17 and the periphery of the ring 17 10 is provided with a series of recesses 20, a recess being provided for each of the inner ribs so that same may be folded in close relation with the telescopic sections when the umbrella as a whole is folded into a compact position.

A coil spring 21 is adapted to be positioned around the ends of each of the stretcher rods 16 as is indicated in Figure 7, one end of the spring is made fast to the 25 stretcher rods, while the opposite end of each spring engages the plate 19, so that in opening or closing the umbrella the spring 21 allows the stretcher rods to give thus preventing the cover 9' from being torn. The ring 17 is provided on its upper face adjacent the central portion of same with a hollow chamber 22, in which is pivoted a pawl 23 and a spring 24 is positioned within the chamber, one end of the spring engaging 30 the rear wall of the chamber while the opposite end of the spring rests in engagement with the pawl 23, and tends to force same into an opening 25 formed in the telescopic section 3, which provides means for supporting the stretcher ring 17 and stretcher 35 rib rods 16 at the desired point on the section 3. The outer end of each of the stretcher rods 16 is connected to the crank 8 as indicated by the numeral 26, the purpose 40 of which will be better understood as the description follows.

From the foregoing description of my invention taken in connection with the accompanying drawings, it can be readily seen that 45 upon sliding the ring 17 on the telescopic section 3 that same will disengage the pawl 23 from the recess 25, and that on continual movement of the ring 17 in the direction of the crown 4 that the stretcher rods 16 are moved first to a horizontal position and then 50 to an inclined position, same assuming a position almost parallel with the inner ribs and during such movement of the rods 16, the cranks 8 are swung on their pivots 7, 55 swinging the ends of the cranks connected to the rods 16 upwardly, thus moving the outer ribs and umbrella cover inwardly and 60 downwardly in the direction of the handle. While being moved inwardly, the outer ribs 65 of each set are swung towards each other on

their pivotal connections 11 to the plates 12, as clearly shown in dotted lines in Figure 3, after which it is an easy matter to move the outer ribs and cover inwardly to the position indicated in Figure 6. It is to be noted 70 that the connection of the plates 12 with the cranks 8 are such that but a slight limited movement of the plates with respect to the cranks is permitted, thus such folding movement as above referred to will not effect the 75 relationship of the plates with the cranks, but will merely cause the outer ribs and cranks to be swung together on the pivotal connections 7 of the cranks.

Telescopic sections 2 and 3 are each provided with a bottom 27 which is slightly larger in diameter than the end of the adjoining section so that it is impossible to move the sections entirely apart.

In order to hold the sections 1, 2, and 3 80 in an extended position, a spring 28 is employed which has one end made fast to the lugs 29 carried by the bottom 27 and the free end of each of the springs 28 are adapted to pass through aligned slots 30 in the 85 connecting sections so that the sections when so positioned are firmly locked until pressure has been brought to bear on the free ends of the springs.

A collar 31 is formed on the upper end of 90 the section 2 and is provided with recesses 32 for the purpose of receiving lugs 33 carried by the underside of the ring 17. Spring arms 34 are pivotally mounted in the collar 31 and upon folding the umbrella and 95 bringing the collar of the telescopic section 2 into engagement with the ring 17 the lugs 33 engage the recesses 32 and are held therein by the spring arms 34.

In Figure 4 I have shown a slightly modified form of fastening the plate 12 to the 100 crank 8. Instead of having the extension formed integral with the plate, I have provided a separate connecting rod as indicated by the numeral 35 that is bolted or made secure in any suitable manner to the plate 12.

From the foregoing description of my invention, it can be readily seen that I have provided a folding umbrella that is not only 105 simple in construction and operation, but durable, efficient for the purpose intended, and one that can be manufactured and placed on the market at a relatively low cost.

While I have shown and described the 110 preferred form of my invention, I realize that various minor changes may be resorted to, without departing from the spirit and scope of the invention as claimed, and therefore, I do not wish to limit myself to the exact details of construction shown, nor to 115 the combination and arrangement of parts.

What I claim as new and desire to secure by Letters Patent is:

An umbrella comprising a staff, a crown 120 mounted thereon, a ring slidably mounted 125

thereon, inner rib sections pivotally connected with the crown, cranks pivotally connected with the free end of the said rib sections, outer rib sections carried by the crank, 5 bracing ribs pivotally connected at their outer ends with the crank and having sliding engagement longitudinally of their

length at their inner ends with the ring, and springs connected with the bracing ribs and the ring. ¹⁰

In testimony whereof I have affixed my signature.

ALBERT J. DANIELSON.
